UNITED STATES PATENT OFFICE

169,720

HELICOPTER

Stefan Apostolescu, New York, N. Y.

Application June 18, 1952, Serial No. 20,251

Term of patent 14 years

(Cl. D71—1)

To all whom it may concern:

Be it known that Stefan Apostolescu, stateless, residing at New York city, in the county of New York and State of New York, has invented a new, original, and ornamental Design for Helicopter, of which the following is a specification, reference being had to the accompanying drawing, forming part thereof.

In the drawing,

Fig. 1 is a top plan view of a helicopter, showing my new design.

Fig. 2 is a side elevational view thereof.

Fig. 3 is a front view thereof.

Fig. 4 is a rear view thereof.

I claim:

The ornamental design for a helicopter, as shown.

STEFAN APOSTOLESCU.
